DESIGN FOR A WASHING MACHINE SUPPORT

Henry Dreyfuss, New York, N. Y., assignor to
The Apex Electrical Manufacturing Company,
Cleveland, Ohio, a corporation of Ohio

Application January 13, 1940, Serial No. 89,453

Term of patent 7 years

To all whom it may concern:

Be it known that I, Henry Dreyfuss, a citizen of the United States of America, residing at New York city, in the county of New York and State of New York, have invented a new, original, and ornamental Design for a Washing Machine Support, of which the following is a specification, reference being had to the accompanying drawing, forming a part thereof.

In the drawing: Figure 1 is a side elevational view; Figure 2 is a front elevational view and Figure 3 is a top plan view of a washing machine support showing my new design.

I claim:

The ornamental design for a washing machine support, substantially as shown.

HENRY DREYFUSS.
